UNITED STATES PATENT OFFICE.

HOWARD M. DUDLEY, OF PHILADELPHIA, PENNSYLVANIA.

DYEING-MACHINE.

1,271,550.

Specification of Letters Patent.

Patented July 9, 1918.

Application filed June 30, 1917. Serial No. 177,954.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to dyeing machines and refers particularly to machines suitable for the dyeing of silk in the form of hanks, hosiery, etc., by means of a circulating dye liquor.

One object of my invention is a device whereby textile fibers may be dyed evenly without manual manipulation.

Another object of my invention is a device in which a dye liquor may be passed in opposite directions through textile fibers.

Another object of my invention is a device in which those portions of the fiber which rest upon the supporting bars are dyed evenly with other portions of the fiber.

Another object of my invention is a device in which the dye liquor is distributed evenly throughout the dyeing chambers.

Another object of my invention is a testing device whereby the condition of the fiber in the dyeing chamber may be determined without opening the dyeing chamber or disturbing the fiber therein.

These and other objects of my invention will be evident upon a consideration of my specification, drawings and claims.

In the dyeing of fibers and fabrics it is necessary that they be moved continuously through the dye liquor or that the dye liquor be passed continuously through them in order that all portions may receive equal treatment to produce even dyeings.

My device overcomes all of the above and other difficulties and presents a method whereby uniform and even dyeing results may be obtained with a minimum of time, labor and expense.

In the accompanying drawings, illustrating modifications of my device, similar parts are designated by similar numerals.

Figure 1 is a vertical cross-section of one form of my device.

Fig. 2 is a cross-section through the line 2-2 of Fig. 1.

Fig. 3 is a top plan view showing the top in a revolved position.

Fig. 4 is a cross-section through the line 4-4 of Fig. 1.

Fig. 5 is a top plan view of a portion of one of the foraminous plates.

Fig. 6 is a broken cross-section through the line 6-6 of Fig. 5.

Fig. 7 is a broken cross-section through the line 7-7 of Fig. 6.

Fig. 8 is a cross-section of a modification of the top and bottom members.

Fig. 9 is a cross-section through the lines 9-9 of Fig. 8.

The form of my device as illustrated comprises a dyeing chamber formed by the side members 10, 11, 12 and 13, abutting upon the members 14, 14, 14, 14, which extend somewhat inwardly from the side members producing a supporting ledge 15, 15 for the purposes explained later. A smaller testing device 16 is adjacent to the side 10, and connected to the lower portion of the dyeing chamber by the conduit 17 and to the upper portion of the dyeing chamber by the conduit 18. The space 19 in the lower portion of the dyeing chamber is connected by the pipe 20, having the valve 21, with the pipe 22 which in turn is connected with the pipe 23. The pipe 23 is connected by means of the pipe 24 with the discharging side of the pump 25. The receiving side of the pump 25 is connected with the pipe 26, having the valve 27, the pipe 26 being connected with the lower part of the reserve tank 28. The pipe 26 is also connected with the pipe 29, having the valve 30, leading to a dissolving tank, not shown. The pipe 23 is connected by means of the universal joint 31 with the pipe 32 having the valve 33. The pipe 32 leads into the chamber 33 formed by the top member 34, capable of being clamped to the side member by the clamps 35, 35. A pipe 36, having the valve 37, leads from the upper portion of the dyeing chamber to the top of the reserve tank 28. A pipe 38, having the valve 39 connects the lower portion of the dyeing chamber with the pipe 36.

The pipe 40, having the valve 41, connects the pump 25 with a source of water supply. Within the dyeing chamber are a series of removable fiber chambers 42, 42^A, 42^B, each

of which is comprised of the foraminous bottom 43, the imperforate sides 44, 44, and the exterior supporting members 45, 45 which are capable of slidable engagement 5 within the indents 46, 46 of the side walls of the dyeing chamber. The upper portion of each supporting member 45, 45 is partially cut away and pins 47, 47 inserted to engage with the hooks 48, 48 whereby the 10 fiber chambers may be removed from within the dyeing chamber.

A foraminous top plate 49 is capable of abutment upon the top of the fiber chamber 42^B.

15 Within the testing chamber 16, a testing fiber chamber 50 similar to the fiber chambers 42, 42^A, 42^B is capable of being supported by the lugs 51, 51, and a foraminous top plate 52 placed thereon.

20 The foraminous plates 43, 43, 49 consist of a series of parallel members comprising upwardly and downwardly divergent members 53, 53, having the openings 54, 54.

Figs. 8 and 9 illustrate a modification of 25 the upper and lower members of the dyeing chamber, comprising the shell within which are the upwardly and downwardly extended members 55, 55 having the openings 56, 56.

The operation of the device is as follows, 30 assuming that the fiber chambers are removed. Each of the fiber chambers 42, 42^A, 42^B is packed with the fiber or fabric to be treated and placed within the dyeing chamber as shown in Fig. 1, the top foraminous 35 plate 49 being placed upon the upper fiber chamber. The top 34, which is in the position shown by the dotted lines 34^A of Fig. 3, is revolved upon the universal joint 31 until it is over the tops of the side members 40 of the dyeing chamber and is then clamped thereto by means of the clamps 35, 35. All 45 of the valves are closed with the exception of valves 30, 21 and 37 and the pump 25 is started. The liquor passes from the dissolving tank, not shown, through the pipes 29, the pump 25, the pipes 24, 22 and 20, the chamber 19, the fiber chambers 42, 42^A, 42^B, and the pipe 36 into the reserve tank 28. When sufficient dye liquor has been brought 50 into circulation, all the valves are closed with the exception of valves 21, 37 and 27. The liquor now passes in continuous circulation from the pump 25 through the pipes 22, 20, chamber 19, fiber chambers 42, 42^A, 55 42^B, pipe 36, reserve tank 28 and pipe 26 back to the pump 25. During this operation, the liquor also passes through the conduit 17, the fiber chamber 50 and the conduit 18 into the chamber 63. When this circulation has been continued for a sufficient 60 length of time, all the valves are closed with the exception of valves 33, 39 and 27. The liquor now passes in a reverse direction from the pump 25 through the pipe 32, 65 chamber 63, fiber chambers 42^B, 42^A, 42,

pipes 38, reserve tank 28 and pipe 26 back to the pump 25. During this operation, the liquor also passes through the conduit 18, the fiber chamber 50 and the conduit 17 into the chamber 19.

Fresh water may be passed through the fiber chambers by means of the pump 25, by opening the valve 41 and closing off the dye liquor supply.

I do not limit myself to the particular 75 size, number, shape, or arrangement of parts, as shown and described, all of which may be varied without going beyond the scope of my invention as described and claimed.

What is claimed, is:

1. In a fiber treating device, in combination, a dyeing chamber, a series of removable fiber chambers within the dyeing chamber, each fiber chamber comprising a foraminous bottom having upwardly extending members and imperforate sides, a foraminous top plate having downwardly extended members to each series of fiber chambers, and means whereby a liquid may be passed in opposite directions through the fiber chambers.

2. In a fiber treating device, in combination, a dyeing chamber, a series of removable fiber chambers within the dyeing chamber, each fiber chamber comprising a foraminous bottom having upwardly extending members and imperforate sides, a foraminous top plate having downwardly extended members to each series of fiber chambers, a second dyeing chamber containing a fiber chamber adjacent to the first dyeing chamber, means connecting the upper and lower portions of the second dyeing chamber respectively with the upper and lower portions of the first dyeing chamber to allow of the passage of a liquid therethrough, and means whereby a liquid may be passed in opposite directions through the fiber chambers.

3. In a fiber treating device, in combination, a dyeing chamber, a series of removable fiber chambers within the dyeing chamber, each fiber chamber comprising a foraminous bottom having upwardly extending members and imperforate sides, a foraminous top plate having downwardly extended members to each series of fiber chambers, means whereby the top of the dyeing chamber may be revolved from the 115 sides thereof to allow of the removal of the fiber chambers, and means whereby a liquid may be passed in opposite directions through the fiber chambers.

4. In a fiber treating device, in combination, a dyeing chamber, a series of removable fiber chambers within the dyeing chamber, each fiber chamber comprising a foraminous bottom having upwardly extending members and imperforate sides, a fo- 125

raminous top plate having downwardly extended members to each series of fiber chambers, a reserve tank, means connecting the upper portion of the dyeing chamber 5 with the upper portion of the reserve tank, means connecting the lower portion of the dyeing chamber with the upper portion of the reserve tank, a pump, means connecting the lower portion of the reserve tank with 10 the pump, and means whereby a liquid may be passed in opposite directions through the fiber chambers.

5. In a fiber treating device, in combination, a dyeing chamber, a series of removable fiber chambers within the dyeing chamber, 15 each fiber chamber comprising a foraminous bottom having upwardly extending members and imperforate sides, a foraminous top plate having downwardly extended members 20 to each series of fiber chambers, a reserve tank, means connecting the upper portion of the dyeing chamber with the upper portion of the reserve tank, means connecting the lower portion of the dyeing chamber 25 with the upper portion of the reserve tank, a pump, means connecting the lower portion of the reserve tank with the pump, a second dyeing chamber containing a fiber chamber adjacent to the first dyeing chamber, means 30 connecting the upper and lower portions of the second dyeing chamber respectively with the upper and lower portions of the first dyeing chamber to allow of the passage of a liquid therethrough, and means whereby a 35 liquid may be passed in opposite directions through the fiber chambers.

6. In a fiber treating device, in combination, a dyeing chamber, a series of removable fiber chambers within the dyeing chamber, 40 each fiber chamber comprising imperforate sides and a foraminous bottom formed by a series of upwardly and downwardly divergent members with openings therethrough for the passage of a liquid, a foraminous top 45 to the upper fiber chamber, and means whereby a liquid may be passed in opposite directions through the fiber chambers.

7. In a fiber treating device, in combina-

tion, a dyeing chamber, a series of removable fiber chambers within the dyeing chamber, 50 each fiber chamber comprising imperforate sides and a foraminous bottom formed by a series of upwardly and downwardly divergent members with openings, therethrough for the passage of a liquid, a foraminous top 55 to the upper fiber chamber, a second dyeing chamber containing a fiber chamber adjacent to the first dyeing chamber, means for connecting the upper and lower portions of the second dyeing chamber respectively with the 60 upper and lower portions of the first dyeing chamber to allow of the passage of a liquid therethrough, and means whereby a liquid may be passed in opposite directions through the fiber chambers. 65

8. In a fiber treating device, in combination, a dyeing chamber, a series of removable fiber chambers within the dyeing chamber, each fiber chamber comprising a foraminous bottom and imperforate sides, the foraminous bottoms being formed by a series of upwardly and downwardly divergent members with openings therethrough for the passage of a liquid, a foraminous top to one of the fiber chambers, swivel means whereby the 70 top of the dyeing chamber may be revolved from the sides thereof to allow of the removal of the fiber chambers, and means whereby a liquid may be passed in opposite 75 directions through the fiber chambers. 80

9. In a fiber treating device, in combination, a dyeing chamber, a series of removable fiber chambers within the dyeing chamber, each fiber chamber comprising a foraminous bottom and imperforate sides, a foraminous 85 top to one of the fiber chambers, the top and bottom of the dyeing chamber having respectively downwardly and upwardly converging foraminous plates for the passage of a liquid, and means whereby a liquid may 90 be passed in opposite directions through the fiber chambers. 90

Signed at Philadelphia, in the county of Philadelphia, and State of Pennsylvania, this 18th day of June, 1917.

HOWARD M. DUDLEY.
